UNITED STATES PATENT OFFICE.

JOHN H. WATTERS, OF AUGUSTA, GEORGIA.

CLEANER FOR BOILER FEED-PIPES.

No. 892,476.

Specification of Letters Patent.

Patented July 7, 1908.

Application filed February 17, 1908. Serial No. 416,412.

To all whom it may concern:

Be it known that I, JOHN H. WATTERS, a citizen of the United States, residing at Augusta, in the county of Richmond and State 5 of Georgia, have invented a new and useful Cleaner for Boiler Feed-Pipes, of which the following is a specification.

This invention relates to improvements in cleaners for boiler feed pipes, and is designed 10 more particularly, though not necessarily, for the feed pipes of locomotive boilers.

The object of the present invention is to provide a cleaning strainer which may be itself readily cleansed when it becomes fouled 15 or clogged by the matters strained out from the feed water.

The invention comprises essentially a straining member or screen mounted on an axis at right angles to the longitudinal axis 20 of the feed pipe and housed in a suitable casing provided with a discharge opening which, when the screen or strainer is in the operative position for removing extraneous matters from the feed water, serves to close 25 the discharge opening so that the feed water will flow from the source of supply directly to the injector for the boiler. When, however, it is desired to clean the screen the latter may be moved at an angle to the feed water 30 so as to uncover the discharge opening without uncovering the conduit on the boiler side. The water finding a means of escape through the exhaust opening will serve to wash off the fouled surface of the screen, and this may 35 be further facilitated by directing a stream of steam against the boiler side of the screen so that the matter collected on the tank side of the screen will be forced away from the latter.

The invention will be best understood from 40 a consideration of the following detail description taken in connection with the accompanying drawings forming part of this specification, in which drawings—

Figure 1 is a longitudinal section of the 45 screen and casing therefor. Fig. 2 is a cross section on the axis of the journal of the screen with the screen shown in elevation, and Fig. 3 is an elevation of the screen and its supporting spindle removed from the casing and 50 showing a slightly modified construction.

Referring to the drawings, there is shown a cylindrical casing 1 from opposite sides of which project necks 2, 3, the neck 2 being externally threaded to receive the threaded 55 collar of a suitable union coupling, and the

neck 3 is internally threaded to receive the threaded end of a pipe. The casing may be connected up in the water conduit in either direction, but for convenience in describing it will be assumed that the neck 2 is on the 60 tank side and the neck 3 is on the boiler side, the structure being considered as being used in connection with locomotive boilers. The casing 1 is cylindrical and has one head 4 formed integral with the cylindrical walls, 65 while the other head 5 is removable therefrom and is secured to the casing by suitable cap screws 6. The head 4 may be formed with a central boss 7 in the inner face of which is formed a socket 8 for the reception 70 of the corresponding end of a shaft or spindle 9. The other end of this spindle extends through a central opening formed in a boss 10 on the head 5, and this boss 10 is counter-bored and threaded for the reception of a 75 packing gland 11 confining suitable packing within the counterbore. The outer end of the shaft 9 beyond the gland 11 carries a crank 12 from which there may be suitable connections to the engine cab in order that 80 the shaft or spindle 9 may be rotated, for a purpose which will presently appear. The shaft or spindle 9 carries a rectangular plate 13, and at about the middle portion of said plate and on one side of the shaft the plate is 85 formed with a prismatic enlargement 14 substantially triangular in cross section. The plate is made fast through a longitudinal diametric slot in the spindle, and on each side of this slot the plate is formed with series of per- 90 forations 15, or any suitable type of screen may be carried by the spindle 9, the purpose being to interpose a screen member between the inlet and outlet ends of the casing for ar- 95 resting any deleterious matter which might be contained in the supply tank before it can reach the injector, and so clog the latter.

The casing 1 is provided about midway be- 100 tween the two necks 2 and 3 with a radial neck 16 having a through passage 17 consti- 105 tuting an outlet for the casing at the bottom of the latter when in position in the feed water supply pipe of the boiler. The en- largement 14 is covered by an inclosing mem- 110 ber 18 which may be made of any suitable material but is preferably made of rubber, and this will fit the inner cylindrical wall of the casing sufficiently close when coincident with the opening 17 to form a closure there- for preventing the escape of water at this

point. When the closure 18, which acts in the nature of a valve for closing the opening 17, is in the proper position to close said opening, then the screen 13 is at right angles to the flow of the water through the casing and the water flowing through said casing must therefore pass through the perforations 15 so that the screen 13 will prevent the passage beyond it of any matters which are not 10 small enough to pass through the openings in the screen. Suppose, now, that the mechanism has been used long enough to become clogged to a greater or less extent and it is 15 desirable to clean the screen, then the latter is moved about its axis by a suitable manipulation of the connections to the crank 12, causing a partial rotation of the spindle 9. This will move the screen away from its 20 normal position until the valve 18 has completely unclosed the opening 17, or even to a point beyond this position. Now, the screen is moved into a more acute angle to the stream of water and the latter will find an 25 escape through the passage 17. This will serve to wash off the material from the face of the screen which has arrested such material, but in order to more effectively cleanse the screen, a stream of steam may be directed back through the pipe from the boiler side of 30 the screen and through the latter, thus blowing off any matter which the water flowing out of the opening 17 will not carry away. The cleansing of the screen is done very quickly so that there is no material waste of 35 the water or steam, and then the screen may be again brought back to its initial position covering the opening 17, and the feed water may then flow to the boiler. It is to be noticed that at no time, whether the screen be 40 in its normal active position or in the position to be cleansed, can the water reach the boiler except through the screen, since at no time is there provided a by-path for the water around the screen.

45 Instead of making the screen of a plate with perforations, it may be made in the form of a suitable frame with metal netting, as indicated in Fig. 3.

What is claimed is:—

1. In a feed water cleaning device, a suitable casing adapted to be interposed in the feed water pipe, said casing being provided with a discharge opening out of line with the normal direction of flow of feed water through the casing and a flat screen mounted in said casing for rotation about an axis at right angles to the direction of the flow of the water, said screen having one edge enlarged to constitute a valve member closing the orifice when the screen is in active position. 50

2. In a feed water cleaning device, a cylindrical casing provided with means for accompanying the same in a feed water pipe and also provided with an exhaust opening out of the line of the flow of water through the 55 pipe, and a rectangular, flat screen member mounted in said casing for rotation about an axis at right angles to the direction of the flow of the water, said screen having one edge enlarged and prismatic in cross section to 60 constitute a valve member arranged to close the exhaust opening of the casing when the screen is in active position. 65

3. In a feed water cleaner for steam boilers, a cylindrical casing formed with diametrically-opposite means for coupling the casing in the feed water pipe and with a discharge opening out of line with the said coupling means, a spindle mounted in the axis of the casing at right angles to the direction of 75 flow of the water, a screen member carried by the spindle and with substantially the same area as the cross sectional area of the casing, said screen member having one edge enlarged, and an elastic covering for said enlarged portion, the said enlarged portion with its covering constituting a valve for closing the discharge opening of the casing 80 when the screen is in its active position. 85

In testimony that I claim the foregoing as 90 my own, I have hereto affixed my signature in the presence of two witnesses.

JOHN H. WATTERS.
